UNITED STATES PATENT OFFICE.

ANDREW L. HILL, OF DECATUR, ILLINOIS.

HAME-FASTENER.

SPECIFICATION forming part of Letters Patent No. 443,520, dated December 30, 1890.

Application filed April 24, 1890. Serial No. 349,358. (No model.)

To all whom it may concern:

Be it known that I, ANDREW L. HILL, of Decatur, in the county of Macon and State of Illinois, have invented certain new and useful Improvements in Hame-Chains, of which the following is a specification.

The object of this invention is to provide a strong and inelastic substitute for hame-straps which may be quickly and easily adjusted in different ways; and the invention consists in the details of construction and combinations of parts hereinafter set forth and claimed.

In the drawings accompanying and forming a part of this specification, Figure 1 represents my device, and Fig. 2 shows one way of using it.

The chain 1 is of ladder construction—that is to say, it has a set of cross-bars regularly arranged. It is flat, it is flexible in one direction, and it may be twisted to a limited extent only. The chain 2 is flexible and twistable. It is attached to chain 1 by means of clasp 7, and it carries the hooked key 3. The connecting-hole of the key is shown at 4, the key at 5, and the hook at 6.

In operation the loop 8 is made to embrace a clip 10 of a hame, the chain 1 is passed through the loop and through the clip 9 of the opposite hame, and a fastening is made 30 by catching the hook 6 on a bar of chain 1 in a readily obvious manner or by passing the key through a space in the chain, as seen in Fig. 2.

The ladder-chain provides a connection for 35 the hook or key, and the twistable chain permits the key-bar to be effectively used.

I claim—

A hame-fastener comprising a chain having rigid transverse bars, a hooked loop attached to one end, and a section of flexible chain carrying a hooked key attached to the other end, substantially as and for the purpose described.

In testimony whereof I sign my name in 45 the presence of two subscribing witnesses.

ANDREW L. HILL.
